UNITED STATES PATENT OFFICE.

GUSTAV LANGEFELD, OF CINCINNATI, OHIO.

WEATHER-STRIP.

968,775.

Specification of Letters Patent. Patented Aug. 30, 1910.

Application filed August 14, 1909. Serial No. 512,792.

To all whom it may concern:

Be it known that I, GUSTAV LANGEFELD, a citizen of the United States, residing at the city of Cincinnati, in the county of Hamilton and State of Ohio, have invented certain new and useful Improvements in Weather-Strips, of which the following is a specification.

My invention relates to that class of weather strips used more particularly in connection with the sills of swinging or hinged windows.

It consists essentially in providing a weather strip composed of a strip of metal combined with an auxiliary metal strip coiled together at the outside or sill side of the window frame and at the inner side of the window frame doubled or folded, the inner side being combined with means for raising or lowering the strip to impinge against the lower face of the sash frame or relieve said strip from impingement.

My weather strip is simple in construction, cheap of manufacture and efficient in use. Its various features and advantages will readily become apparent from the following specification.

In the accompanying drawing, forming a part of this specification, Figure 1 is a perspective view of a window sash and jamb, partly broken away to illustrate construction, with my weather strip in position. Fig. 2 is a sectional view taken at line X, X, of Fig. 1, the weather strip shown away from the lower side of the sash frame and not in impingement therewith. Fig. 3 is a similar view to that shown in Fig. 2, except that the weather strip is shown in impingement with the lower side of the sash frame. Fig. 4 is an enlarged view of the weather strip and means for raising and lowering it attached thereto to show the relation between said parts. Fig. 5 is a view of the means for raising and lowering the weather strip, partly broken away to illustrate construction.

The jamb is marked 1, the window sash 2, the window sill 3. The sash 2 is usually hinged at 4.

The weather strip consists of a metal strip 5 at its outer side coiled or curved around on rod or bar 6 and at its inner side doubled or folded, first extending upward and then bent downward, the downward bend extending down beyond the strip 5. The upward bend or fold is marked 7 and the downward bend

or fold 8, a slight space is left between the folds 7 and 8, marked 9. An outer or auxiliary strip 10, curled or coiled around the wire or rod 6, similarly to strip 5, extends out into the window sill 3 and has its outer edge bent down to form an elongated tang or cleat 12, which is forced into the sill 3 to hold rigidly and tightly. At each end where the weather strip reaches the jamb, said jamb 1 is cut away or recessed as shown at 14 and the strip 5 is bent up as shown at 15, so that the strip 5 with its fold 7 at the inside and its upturned ends 15, may be said to form a pan. The means for raising and lowering the weather strip (or pan) 5 is connected to said fold 8, and consists of a box 16 screwed to a sill or stool, with which said windows are usually provided. This box holds a rack 17 which moves up and down in the box, (see particularly Fig. 5). Inside the box 16, I place a pinion or small gear wheel 18 connected rigidly to a lever 19, the teeth on the pinion 18 meshing with the teeth on rack 17 when the lever 19 is moved forward or backward. The rack 17 carries a jaw 20 into which jaw passes the downward fold or bend 8 of the strip or pan 5, being securely connected to said strip 5, so that when the lever 19 is moved forward and backward the rack 17 which carries said jaw 20 will carry the pan 5 up and down with it as the pinion 18 meshes with said rack. One of these boxes and connections may be placed at each end of the weather strip as shown.

It will be readily seen that the sash when swung in will slightly impinge against the coiled head 21 formed by the curved, coiled or curled ends of the strips 5 and 10, rigidity and strength being given to said coiled head 21 by the bar 6; this in itself making a tight joint at the outside of the window. When the lever 19 of the raising and lowering means is operated to raise the strip or pan 5, the said strip or pan moves up and impinges against the lower face of the sash as shown in Fig. 3, the folds 7 and 8 rising above the lower edge of the sash and the ends 15 of the pan or strip 5 passing up into the recesses 14, thus forming a water tight and dust proof joint and also preventing air from entering through the window at the point where the weather strip is present, either along the lower edge of the window at the sill, or at the edges at the jamb, the water, rain or the like always being turned outward to the sill, thus forming a

tight joint along the entire lower portion of the window and its corners. When the weather strip is in this position the window cannot be opened. If it is desired to open 5 the window, the lever 19 is turned in an opposite direction and the strip will be lowered to a position shown in Fig. 2, when the sash can pass over the strip to an open position.

The strip may be formed of any other 10 shape or contour and from any material and be connected to the window frame or sill in any desired manner.

The means for raising and lowering the 15 strip may be of any other construction than that herein specifically shown and described.

The coiled head may be constructed any 20 other way and the weather strip with slight modifications may be connected to windows of other form and construction.

What I claim as new and of my invention and desire to secure by Letters Patent 25 is:—

1. In a weather strip of the character de-

scribed, a metal pan shaped strip, recesses 25 provided in the window jamb, said pan shaped strip provided with means for raising and lowering it up against and away from the lower face of the window sash, said pan shaped strip when being raised and lowered at its ends also moving up and 30 down in said recesses in the jamb, as set forth.

2. In a weather strip of the character described, two metal strips, one passing toward the outside of the window and the other 35 toward the inside of the window, said strips at their meeting point coiled to form a head, a rod passing through said head, the outer strip rigidly connected to the window sill, the inner strip movably connected to the 40 inside of the window, as set forth.

GUSTAV LANGEFELD.

In the presence of—

HENRY BAER,
JOHN W. STREHLI.
